UNITED STATES PATENT OFFICE.

THOMAS CHIPERA, OF BRECKENRIDGE, MINNESOTA.

SIEVE FOR FANNING-MILLS.

No. 910,904.

Specification of Letters Patent.

Patented Jan. 26, 1909.

Application filed June 4, 1908. Serial No. 436,654.

To all whom it may concern:

Be it known that I, THOMAS CHIPERA, a citizen of the United States, residing at Breckenridge, in the county of Wilkin, State 5 of Minnesota, have invented certain new and useful Improvements in Sieves for Fanning-Mills; and I do hereby declare the following to be a full, clear, and exact description of the invention, such as will enable others 10 skilled in the art to which it appertains to make and use the same.

This invention relates to sieves for fanning mills, and has as its primary object to improve the efficiency of such devices.

15 In the sieve embodying my invention there is provided a stationary frame and a frame mounted within the stationary frame for reciprocatory movement and in the stationary frame are journaled peripherally 20 grooved rollers, there being wires strung in the reciprocatory frame and traveling in the groove in the rollers the grooved rollers serving to hold the wires in spaced relation at all times. In addition to this feature of the in- 25 vention, the wires are alternately of large and small diameters so that as the grain is discharged upon the reciprocatory frame and of course upon the wires, it will be stood on end and its separation be had with a greater 30 degree of fineness and in a more perfect manner than if the wires were all of the same diameter.

In the accompanying drawings, Figure 1 is a top plan view of the sieve embodying my 35 invention, Fig. 2 is a side elevation thereof, Fig. 3 is a vertical longitudinal sectional view therethrough, Fig. 4 is a vertical trans- 40 verse sectional view taken in a plane with one of the peripherally grooved rollers, Fig. 5 is a detail perspective view of a portion of one of the peripherally grooved rollers and several of the wires.

As shown in the drawings, and as heretofore stated, the sieve embodying my invention 45 comprises a main frame and a reciprocatory frame and the main frame is made up of side sills 10, and an end cross sill 11, the said sills serving to connect the upper ends of the side sills, and an end board 12 secured 50 at its side edges to the under side of the side sills 10 adjacent their lower ends. A cross sill 13 also connects the lower ends of the side sills and at its lower edge rests upon the upper face of the end board 12 it being un- 55 derstood that the said end board, the said cross sills and the lower end of the side sills

form a box or receptacle into which the wild oats is to discharge.

Mounted for rotation in the main frame of the sieve and transversely thereof are rollers 60 14 and each of these rollers is formed with a plurality of peripherally extending grooves 15 the said grooves being of such number as to extend practically throughout the entire length of the rollers. The function of these 65 rollers will presently be more specifically stated. Secured to the outer side faces of the side sills 10 of the main frame of the sieve are guide plates 16 the said plates being ex- 70 tended above the upper faces of the said side sills and serving to guide, between them, the supplemental or reciprocatory frame of the sieve which will now be described.

The reciprocatory frame mentioned above 75 comprises side sills 17, a cross sill 18 which connects the lower end of the said side sills, and a cross sill 19 which connects the side sills 17 at their upper ends. A sheet metal plate 20 is secured at its side portions beneath the rear end of the side sills 17 and 80 this plate is extended forwardly between the under side of the said side sills and the cross sills 19 which connect the upper end of the said side sills, the rear edge portion of the plate being bent to extend vertically as in- 85 dicated by the numeral 21. Strung longitudinally in the reciprocatory frame are wires 22 and 23 the wires 22 being alternated with those of the series 23 and being of less di- 90 ameter than the wire 23 these wires being spaced a slight distance apart as to permit 95 cultivated grain to fall between them. The under side of the wires 22 and the wires 23 are in a common plane and as a consequence an uneven upper or top surface is the result 95 it being understood that when grain is de- 100 posited upon the wires and the reciprocatory frame reciprocated, the grain will be turned to lie longitudinally of the frame and the cultivated grain will fall between the wires 100 and into a suitable receptacle arranged beneath the frame of the sieve. The wild oats will travel down the wire and fall over the lower end of the reciprocatory frame and into the receptacle formed by the side sills of 105 the main frame, the lower cross sill thereof, and the cross board 12.

In the drawings I have shown merely the 110 sieve embodying my invention and have omitted any showing whatsoever of the mill in which the sieve is arranged and also the means for reciprocating the supplemental

frame of the sieve as such construction would only be confusing and forms no part of my invention, it being understood of course that the sieve illustrated and described may be used in any relationship found expedient, and that it is inclined.

What is claimed is:

1. A sieve for fanning mills comprising a stationary frame, a reciprocatory frame 10 mounted in the stationary frame, wires strung in the reciprocatory frame, said wires being alternately of large and small diameter, the under sides of the strands of wire being in a common plane, and means to actuate 15 the reciprocatory frame.
2. A sieve for fanning mills comprising a stationary frame, a reciprocatory frame mounted in the stationary frame, wires strung in the reciprocatory frame, said wires 20 being alternately of large and small diameter, the under sides of the strands of wire being

in a common plane, rollers supporting said wires, and means to actuate the reciprocatory frame.

3. A sieve for fanning mills comprising 25 a stationary frame, a reciprocatory frame mounted in the stationary frame, wires strung in the reciprocatory frame, said wires being alternately of large and small diameter, rollers supporting said wires provided with 30 grooves of alternate large and small radius and having their bottoms in a common cylindrical surface whereby the wires are supported in a common plane, and means to actuate the reciprocatory frame. 35

In testimony whereof, I affix my signature, in presence of two witnesses.

THOMAS CHIPERA.

Witnesses:

P. E. TRUAX,
P. F. GERGEN.
